PERMUTATION PADLOCK.
APPLICATION FILED OCT. 29, 1912.

Patented June 30, 1914.

2 SHEETS-SHEET 2.

UNITED STATES PATENT OFFICE.

FRANK RADASZEWSKI, OF NIAGARA FALLS, NEW YORK.

PERMUTATION-PADLOCK.

1,102,167.

Specification of Letters Patent. Patented June 30, 1914.

Application filed October 29, 1912. Serial No. 728,481.

To all whom it may concern:

Be it known that I, FRANK RADASZEWSKI, a citizen of the United States, residing at Niagara Falls, in the county of Niagara and State of New York, have invented a new and useful Permutation-Padlock, of which the following is a specification.

One object of the present invention is to provide a permutation padlock having novel mechanism for operatively connecting the shackle with the tumblers. The invention aims further, to provide a permutation padlock which will work noiselessly, and which may be operated without the use of springs. It is within the scope of the invention, to increase the utility of devices of that type to which the present invention appertains.

With the foregoing and other objects in view which will appear as the description proceeds, the invention resides in the combination and arrangement of parts and in the details of construction hereinafter described and claimed it being understood that changes in the precise embodiment of invention can be made within the scope of what is claimed without departing from the spirit of the invention.

In the drawings:

Figure 1 is a front elevation; Fig. 2 is an elevation, the closure for the lock case being removed, sundry parts being sectioned, and the bearing plate being broken away. Figs. 3, 4 and 5 are plans of the tumblers; Fig. 6 is a transverse section of one tumbler; Fig. 7 is a section of the lock on the line 7—7 of Fig. 2; Fig. 8 is an end elevation of the lock; Fig. 9 is a fragmental elevation showing the position of the index with respect to the case of the lock; Fig. 10 is a fragmental perspective showing the relation between the tumbler index and the case of the lock; Fig. 11 is a perspective of the dog; Fig. 12 is a perspective of the removable dial; and Fig. 13 is a perspective of the latch.

The case of the padlock herein disclosed comprises a box-like body 1, open at one side, and provided at one end with openings 2 and 3. In the edge of the top of the body 1 there is a notch 4 and in the edge of one side wall of the body there is another notch 5 (see Fig. 8). The notches 4 and 5 are adapted to receive lugs 6 which project from the edges of a bearing plate 7. But one lug 6 is shown, the same appearing in Fig. 8, but referring to the upper left hand portion of Fig. 2 it will be readily appreciated by any person

skilled in the art that the plate 7 shown broken away, may be provided with another lug adapted to register in the notch 4. The bearing plate 7 is supported by a collar 8, 60 surrounding a rivet 9 which secures the bearing plate 7 to the body 1. Another rivet 9^a may be employed for securing the bearing plate 7 to the body portion 1 of the padlock. The bearing plate may be held in 65 place, further, by a shaft 10 which is connected with the body 1. The invention includes a closure 11 for the open side of the body 1, the closure 11 being provided with lugs 12 (see Fig. 8) which are received in 70 the notches 4 and 5. But one lug 12 is shown in Fig. 8, but a skilled mechanic examining Fig. 2 will understand readily that the other lug 12 registers in the notch 4. The closure 11 may be held in place by a rivet 14 or like 75 device which engages the body 1.

Journaled for rotation in the body 1 and in the bearing plate 7 is a tumbler shaft 15, upon which are mounted to rotate tumblers 16, 17 and 18, the tumblers having openings 80 or notches 19 in their peripheries, which notches or openings may be brought into alinement by rotating the tumblers. The tumblers are spaced by hubs 20 and no novelty is claimed by the specific form of tumblers shown. In the tumbler 17 is mounted a pin 21 which projects beyond opposite faces of the tumbler, the pin 21 being adapted to coöperate with a similar pin 22 in the tumbler 16, one end of the pin 21 coöperating with a pin 23 in the tumbler 18. The tumbler shaft 15 is equipped with a radial finger 24 which is adapted to engage one end of the pin 22 in the outermost tumbler 16. 95

The invention further includes a dog 25 which, as clearly shown in Fig. 2, is in slideable contact with one wall of the body 1 of the lock. The dog 25, as shown in Fig. 11 is equipped with an opening 26, receiving the 100 stem 27 of a button 28, the button 28 being located upon the outside of the body 1 and the stem 27 being mounted to slide in a slot 29 in the body. At one end, the dog 25 is provided with an arm 30, terminated in a 105 finger 31 which may be moved into the openings 19 in the tumblers 16, 17 and 18, when these openings are alined. When the openings 19 in the tumblers are not alined, the peripheries of the tumblers ride along the 110 end face of the finger 31, and consequently the dog 25 cannot be slid through the medi-

um of the button 28. At its other end, the dog 25 terminates in an arm 32 having a reduced neck 33 provided with a transverse head 34. The neck 33 lies in a notch 35 formed in one arm 36 of a latch 37, the head 34 extending across the bifurcations defined by the notch 35. The latch 37 includes an arm 38 and an arm 39, the arm 39 having an opening 40, receiving the shaft 10, so that the shaft 10 constitutes a pivotal support for the latch. The end face of the arm 38 is beveled as indicated at 41.

There is provided in carrying out the invention, a slidable shackle which is denoted generally by the numeral 42. The shackle 42 comprises a relatively short arm 43 which slides in the opening 3, and a longer arm 44 which slides in the opening 2. The arm 44 terminates in a beveled extension 45 received between the rivet 9^a and the adjacent wall of the case. In the edge of the arm 44, there is a notch 46 defining a shoulder 47. When the shackle is in locked position, as shown in Fig. 2, the beveled end 41 of the arm 38 of the latch 37 registers in the notch 46. The lower edge of the shoulder 47 is beveled as indicated at 47.

The tumbler shaft 15 is provided, upon the outside of the body 1, with a hub 48, carrying a crank 49 constituting an index. As shown in Fig. 9, the index or crank 49 is spaced apart from the outer face of the body 1. A manually removable dial 50 is provided, the same having a circular opening 51 adapted to fit around the hub 48 of the tumbler shaft, the dial 50 lying between the index or crank 49 and the outer face of the case 1. The opening 51 is provided with a radial slot 52 which permits the passage of the crank 49. The dial 50 is supplied, with an angularly disposed wing 53 which is adapted to lie along one edge face of the body 1 of the lock case. The dial 50 may be provided with a plurality of points 54, and upon the face of the dial 50 may be inscribed a plurality of characters 55. These characters 55 may spell the name of the owner of the lock. In the dial 50 there is a hole 56, whereby the dial may be assembled with a key ring.

When the parts are in locked position, the arm 38 of the latch 37 will engage in the notch 46 of the arm 44 of the shackle 42 and hold the arm 43 of the shackle in the opening 3. The latch 37 cannot tilt upon its pivotal mounting 10, because the arm 36 of the latch is upheld by the arm 32 of the dog 25. The dog 25 cannot be slid, because the end of the finger 31 of the dog is located close to the peripheries of the tumblers 16, 17 and 18.

When it is desired to open the shackle 42, the dial 50 is mounted in place, the opening 51 in the dial receiving the hub 48 of the tumbler shaft 15 and the crank 49 of the

tumbler shaft passing through the radial slot 52. The wing 53 of the dial lies against one edge of the body 1 of the lock case, and thus the dial is held against radial movement.

In setting up the combination, the crank or index 49 may be made to register upon the points 54 of the dial 50 or the characters 55 may be used to set up the combination. When the characters 55 are employed for this purpose, the points 54 act as a blind, and when the points 54 are employed, the letters 55 act as a blind.

The general operation of a permutation padlock is well understood, and it will be understood that when the tumbler shaft 15 is manipulated, as hereinbefore described, to set up the combination, the finger 24 will engage one end of the pin 22 in the tumbler 16 the other end of the pin 22 engaging one end of the pin 21 in the tumbler 17, the other end of the pin 21 in the tumbler 17 engaging the pin 23 in the tumbler 18, the tumbler shaft 15 being rotated first in one direction and then in another direction until the cooperation between the several pins 22, 21 and 23 alines the notches 19 in the tumblers. When the notches 19 in the tumblers are alined, the dog 25 may be slid through the medium of the button 28 until the finger 31 enters the alined notches 19. When the dog is slid in the manner hereinbefore described, the dog will swing the latch 37 upon its pivotal mounting 10 and withdraw the end of the arm 38 from the notch 46 in the arm 44 of the shackle 42. Thereupon the shackle may be withdrawn, so that the arm 43 is moved from the opening 3.

In order to place the parts in locked position the shackle 42 is pushed into the lock case, whereupon the beveled edge 47^a of the shoulder 47 will engage upon the beveled edge 41 of the arm 38 of the latch 37 to effect a tilting of the latch, so that the shoulder 47 will ride past the end of the arm 38, the shackle 42 under such circumstances, appearing as shown in Fig. 2. During the sliding of the dog 25, as above described, the finger 31 enters the notches 19 in the tumblers 16, 17 and 18, and it is therefore evident that the parts may be positioned in locked position, only when the combination has been set up, to aline the notches 19. It is necessary, therefore, that a person should be acquainted with the combination, if the shackle 42 is to be placed in the locked position as shown in Fig. 2. An unauthorized unlocking of the structure, will, therefore, be as difficult as an unauthorized locking thereof.

The dial 50 is removed, so soon as the locking operation has been finished, and therefore there remains upon the lock, no index of any sort whatever, giving a hint

as to the operation of the structure. The combination may be changed by replacing one dial 50 by another dial of different form, it being unnecessary to take the lock apart 5 or to shift the tumblers, when the combination is to be changed. It is to be noted that the lock is devoid of springs and that it will operate without noise.

Having thus described the invention, what 10 is claimed is:—

1. A permutation padlock comprising a case; a tumbler journaled therein and having an opening; a shackle movable in the case; a latch coöperating with the shackle 15 and fulcrumed intermediate its ends on the case; a dog upheld by one end of the latch and pivotally connected therewith and constituting the sole means for moving the latch to dispose the other end thereof in 20 the path of the shackle, the dog being accessible from the outside of the case, and a part of the dog being adapted to register in the opening in the tumbler.

2. A permutation padlock comprising a case; a tumbler journaled in the case and having an opening; a dog mounted for right-line sliding movement in the case and accessible from the outside of the case, a portion of the dog being adapted to register in the opening in the tumbler; a latch pivoted to the case and to the dog; a movable shackle in the case, the shackle being provided with a shoulder adapted to engage the latch, the shoulder being movable into 30 locked and unlocked relation to the latch only when the dog is in said opening.

3. A permutation padlock comprising a case; a tumbler journaled in the case and provided with an opening; a dog in slide- 40 able contact with one wall of the case, the dog being provided with substantially parallel projecting arms, one of which is provided with a finger adapted to register in the opening in the tumbler; a button upon 45 the dog, accessible from the outside of the case; a latch pivoted in the case and pivotally connected with the other arm of the dog independently of the case; and a shackle 50 slideable in the case and engageable by the latch.

4. In a permutation padlock, a case; a shackle movable in the case; a latch pivotally supported intermediate its ends upon the case, one end of the latch coöperating 55 with the shackle and the other end of the latch having bifurcations; a dog slideable upon the case and provided with substan-

tially parallel arms, one arm terminating in a finger and the other arm terminating in a reduced neck located between the bifurcations and having a transverse head engaging the bifurcations, the dog being accessible from the outside of the case; and a tumbler movable in the case, the tumbler having an opening receiving the finger. 65

5. In a permutation padlock, a case; a dog held for right-line sliding movement on the case and accessible from the outside of the case; a shackle movable in the case; a latch pivoted in the case and coöperating with the shackle, the latch having a loose pivotal connection with the dog to permit right-line movement of the dog; and a tumbler journaled in the case, the tumbler coöperating with the dog. 70

6. A permutation padlock comprising a case; a shackle movable within the case and having a shoulder; a latch pivoted in the case and coöperating with the shoulder; a dog pivoted to the latch and supported for sliding movement on the case, the dog being accessible from the outside of the case; and a tumbler journaled in the case and having an opening in which the dog is adapted to register, a part of the dog engag- 80 ing the periphery of the tumbler after the tumbler has been rotated to move the opening therein out of alinement with said part of the dog both when the shoulder is above and below the latch, thereby preventing 85 either an opening or a closing of the shackle, saving when the dog is in the opening in the tumbler.

7. In a permutation padlock, a case; a shackle movable in the case; a latch pivoted 95 in the case and coöperating with the shackle; a dog accessible from the outside of the case and held to the case for sliding movement in a certain direction, the dog being loosely secured to the latch, whereby the weight of the dog will tend to swing the latch toward the shackle, and whereby the latch may move with respect to the dog while the latch is being actuated by the dog; and a tumbler in the case, with which tumbler the dog coöperates. 100

In testimony that I claim the foregoing as my own, I have hereto affixed my signature in the presence of two witnesses.

FRANK RADASZEWSKI.
